UNITED STATES PATENT OFFICE.

CHARLES OTIS PALMER, OF CLEVELAND, OHIO.

MINING-MACHINE.

SPECIFICATION forming part of Letters Patent No. 594,897, dated December 7, 1897.

Application filed April 18, 1894. Serial No. 508,022. (No model.)

To all whom it may concern:

Be it known that I, CHARLES OTIS PALMER, a citizen of the United States, residing at Cleveland, in the county of Cuyahoga and State of Ohio, have invented certain new and useful Improvements in Mining-Machines, of which the following is a specification, reference being had to the accompanying drawings.

Although many of my improvements are applicable to other classes of excavating-machines, yet my invention relates more especially to improvements in that class of mining-machines in which the cutting apparatus is carried by a swinging arm journaled in the turret of the mining-machine frame and is in the nature of an improvement on the mining-machine described in my patent No. 472,177, dated April 5, 1892.

Among other things these improvements consist in the skeleton form of frame employed, which secures the requisite strength with a minimum weight; in the elastic support under the forward end of the mining-machine, which allows of a greater range of irregularity of the floor without interfering with the working of the machine and at the same time secures a more true and uniform floor-surface; in the construction of the track to more effectually resist the thrust of the cutters when in operation; in the arrangement for grooving the floor, giving a firm brace for the track and securing a uniform parallel advance cutting movement of the mining-machine; in the swinging movement of said router, which allows it to be turned upward clear of the floor to prevent injury during the placing and loading and unloading of the machine, as well as during its transportation; in the means of feeding the machine when making the straightcut; in the means of feeding the machine to make the rotary cut; in improved means for communicating power to the cutter-wheel; in improved means for holding the machine while inspecting, removing, and inserting the cutter-chisels; in various details connected with the inserted chisels employed for cutting the coal and in the means for securing them in place; in means for automatically removing the slack formed by the cutter-wheel; in the improved form of constructing the cutter-carrier to cheapen the cost of manufacture and facilitate repairs,

and in the combination and arrangement of parts intended to simplify and strengthen the mining-machine and to better adapt it for its intended purpose, as will be hereinafter explained, and pointed out in the claims.

In the drawings forming part of this specification, Figure 1 is a plan of the machine embodying my present improvements. Fig. 60 2 is an end view of the machine shown in Fig. 1. Fig. 3 is a section on line G H of Fig. 2. Fig. 4 is a longitudinal section with the cutter-wheel swung under the frame. Fig. 5 is a view of the right side of the machine with 65 the cutter-wheel in the position shown in Fig. 1. Fig. 6 is a horizontal section approximately in line S T in Fig. 5. Fig. 7 is a section in line I J, Fig. 6. Fig. 8 is a detailed view of the clutch q^3 in the worm-wheel q^2 and is similar to the clutch t^4 in the worm-wheel t^3 . Fig. 9 is a diagram showing a top view of the machine when nearing the end of its straight cut. Fig. 10 is a top and a side view in projection of the track shoe-clips x^5 . Fig. 11 is 70 a plan of a mine-room, illustrating the mode of operating the machine. Fig. 12 is a detailed plan and edge view of part of the left rail of the track for operating the mining-machine. Fig. 13 is a detailed plan and edge 75 view of part of the right rail. Fig. 14 is a transverse section of the track. Fig. 15 represents two views in projection of the wrench for adjusting the turret-feet. Fig. 16 represents two views in projection of the crank- 80 handle for operating the cross-feed shaft K, feed-drum shaft l' , and rotary-feed shaft q by hand. Fig. 17 is a top view of the cutter-wheel with part broken away to show the groove for the escape of the slack on the 85 under side of the rim. Fig. 18 is an edge view of the cutter-wheel shown in Fig. 17, so that the bottom side is up. Fig. 19 is a section of the cutter-wheel on line K L of Fig. 17. Fig. 20 is an edge view of the cutter-wheel as in 90 the ordinary position, with the top side up. Fig. 21 is an enlarged section through the cutter-wheel pinion just below the housing and above the cutter-wheel. Fig. 22 is a vertical section on line Q R of Fig. 21. Fig. 23 95 is a vertical section on line M N of Fig. 17, showing the inclination of the middle cutter-chisels. Fig. 24 is a vertical section on line O P of Fig. 17, showing the inclination of the

outside cutter-chisels. Fig. 25 is a detail in projection of the side and edge views of the cutter-chisels. Fig. 26 is a detail in projection of the top, side, and edge views of a 5 middle chisel-wedge. Fig. 27 is a detail in projection of the side, edge, and bottom of an outside chisel-wedge. Fig. 28 illustrates a modified form of my cutting device. Fig. 29 is a modified form of my elastic support. 10 Fig. 30 is a side view of a modified form of my router. Fig. 31 is a vertical longitudinal section of the router shown in Fig. 30. Fig. 32 is a plan end view of an outside cutter-wedge in place.

15 The frame of my improved mining-machine consists of two sides c c , attached at their diverging ends to the track-shoes c^2 c^3 , which are secured to the extremities of the cross-brace c' . Between the converging ends of the 20 sides c c is held the turret-ring c^5 by having its side bars c^6 c^6 attached to the said machine-frame sides. Extending across the middle of the machine-frame and joining the extremities of the turret side bars c^6 c^6 is the middle 25 brace c^7 , which is strengthened by cross-braces c^8 c^8 , extending to the turret-ring c^5 , and between said cross-braces is held a boss, into which the center stud c^9 is inserted with a driving fit. Journaled on the center stud c^9 30 is the beveled stud-gear d^4 , on whose elongated shank are keyed the driving-pinion d^5 and the driving-pulley d^6 . The upper end of center stud d^3 is tapped to receive the screw-eye d^7 , which passes through and holds the 35 washer d^8 in place. The screw-eye d^7 is used in raising the machine for inspecting, adjusting, or removing the cutter-chisels e^8 .

Bolted to the upper side of the cutter-carrier e and journaled in the turret-ring c^5 is 40 the turret-worm wheel e' , which also acts as a journal for the cutter-carrier e . An opening is made through the web of said turret-ring and flanges formed on the outside of said ring on the top and bottom sides of said opening; also, vertical ribs are formed at the ends of said opening connecting said flanges together and to the web of the turret-ring. The 45 said flanges and webs form a housing for the turret-worm. The outer side of said housing is also inclosed to protect the worm and further increase the strength of the turret-ring. By this construction the turret-ring is reinforced at what would otherwise be the weakest point by the top and bottom flanges, that 50 add greatly to its strength. Besides, the vertical ribs serve as braces to take the end thrust of the worm. Engaging with said worm-wheel e' is the turret-worm e^3 , by which it is driven. The said cutter-carrier journal is prevented 55 from end motion in the turret-ring c^5 by its own flange on its upper side and by the cutter-arm e , which forms the lower flange. Secured to the under side of the opposite end of the cutter-carrier e by the screws e^5 is the plate-bearing e^4 , on which revolves the cutter-wheel e^6 .

There are some very important advantages

secured by having the worm-wheel within the turret-ring. It occupies less room vertically than would be the case if the worm-wheel 70 was placed on the flange at the end of the bearing and thereby reduces the height of the machine. The application of the rotating force between the ends of the bearing brings less strain on the frame than would otherwise 75 be the case. The worm-gearing being entirely covered by the bearing protects it from the coal-dust as well as injury by contact while being transported.

The cutter-carrier has heretofore been cast 80 in one piece with its journal, making thereby quite a heavy piece, and one that required unusually large and expensive tools to do the turning and gear-cutting on the same. My cutter-carrier journal being made in a separate 85 piece and bolted on the carrier allows the turning and gear-cutting to be done on much smaller and less expensive tools, while the facing on the arm e is done on a planer of ordinary size.

90 My improved cutter consists, in a general way, of a large thin cutter-wheel e^6 , with gear-teeth e^7 on its periphery and having a hub and spokes about half the thickness of the rim. A portion of the gear-teeth are mortised 95 to admit an inserted chisel e^8 , that projects beyond its periphery to operate on the coal. Said chisels e^8 are straight pieces of steel of uniform section file-cut or roughened on one side and suitably tempered.

100 My cutter-chisels being of uniform section are cheaply manufactured, and they have the advantage in sharpening that they only need grinding on the end and do not require forging. The chisels when new and long are used 105 for outside cutters, where the long shank helps to secure the chisel against sidewise displacement; but after being worn down shorter by repeated sharpening they answer 110 for middle cutters, where they are completely surrounded in the mortise to within a short distance of the end and there is little tendency for sidewise displacement.

115 As heretofore made the cutter-wheel spokes have been radial, and as their motion was at right angles to the radial spokes the slack on the bottom of the kerf was simply scraped round and round with the wheel, obstructing its progress, clogging its movement, and uselessly consuming power.

120 The arms d^9 of my cutter-wheel, as herein shown, incline from the hub backward toward the rim in the direction opposite to the direction of motion when in use. As material moved with a slanting scraper gradually 125 slides off the receding end of the scraper, so the slack made by the cutters is scraped toward the rim of the wheel. The gear-teeth are so arranged that a tooth projects from the rim of the wheel in line with each spoke, and 130 on the under side of the rim, preferably between the said tooth and the one preceding, is a groove v^5 , along which the slack scraped by the spoke escapes from the cutter-wheel.

Removable cutters have heretofore projected from the face of the cutter-wheel and been held in position by wedges secured in place by set-screws inserted and turned from the outside of the wheel. In order to allow the head of the set-screw to pass between the teeth of the driving-pinion, it necessitates a very wide tooth on the cutter-wheel gear, thereby increasing the pitch of the teeth and decreasing the number of teeth on the driving-pinion, which is always too small at best. This small number of teeth in gears, as is well known, greatly increases the friction and consequent loss of power and wear on the teeth. In my cutter-wheel the screw enters from the inside of the rim, thus allowing of a narrower cutter-wheel tooth of correspondingly less pitch, with the consequent increase in number of pinion-teeth and the consequent diminution of waste friction.

In order that the mortises for the chisels may not weaken the tooth too much, they are made much narrower than the thickness of the rim. In this case it requires the combined cutting edges of four cutter-chisels e^8 placed side by side to equal the height of the kerf made by the cutter-wheel. These four cutter-chisels constitute a set and are arranged to follow each other successively on the cutter-wheel. There may be one or more sets on a cutter-wheel, as may be determined by the hardness of the coal, the depth cut by the chisel, &c. In the present instance there are four sets which follow each other successively around the circumference of the cutter-wheel.

The cutter-chisels e^8 are held in position by the cutter-wedges i^2 i^3 , whose side next the chisel is file-cut or roughened to fit the file-cut or roughened adjoining side of the cutter-chisel. Each cutter-wedge is tapped longitudinally to admit the wedge-screw i , that enters the cutter-wheel rim from the inside and lies parallel to the cutter-chisel e^8 . On the under side of the head of said wedge-screw i is the washer i' , against which the screw is turned and which covers the chisel mortise-holes in the wheel-rim. In each set there are two outside cutter-chisels i^3 , that project beyond the cutter-wheel both on the upper and lower planes, and two middle chisels i^2 , that stand at a less angle with the cutter-wheel and cover the remainder of the kerf not cut by the outside cutter-chisels. Fig. 23 shows the position of the middle cutter-chisels in the cutter-wheel, and Fig. 24 shows the position of the outside cutter-chisels which project beyond the plane of the cutter-wheel, as already mentioned. The outside cutter-chisels have a cutter-wedge i^3 , that is dovetailed on the edge opposite the cutter-chisel, as is shown in Figs. 27, 17, and 18. By file-cutting or roughening the adjacent sides of the cutter-wedge and cutter the friction between them is increased and they are so prevented from slipping on each other. As long as there is no slipping between them

any end pressure on the cutter tending to drive it radially into the wheel only serves to press the wedge tighter and hold the cutter firmer in place. Likewise with the dovetail wedge any force tending to displace an outside cutter outward from the wheel only tends to set the wedge tighter against the cutter and thus hold it firmer in place.

Supported in the center of the turret-worm wheel e' by the radial arms d' is the turret-hub d , and journaled in this hub centrally of the turret-ring c^5 is the cutter-wheel-pinion shaft d^2 . Keyed onto the lower extremity of shaft d^2 and engaging with the teeth of the aforesaid cutter-wheel e^6 is the cutter-wheel pinion e^9 , having the upper end of its teeth shrouded, as shown, in the ordinary manner. On the upper end of the cutter-wheel-pinion shaft is keyed the intermediate gear e^2 , that engages with the driving-pinion d^5 , which is journaled, as aforesaid, on the center stud c^9 .

Projecting from the under side of the cutter-carrier outside the cutter-pinion are one or more (in this case three) elastic supports or feet by which the forward end of the mining-machine is carried. These elastic supports consist each of a vertical screw g , having a large head on its lower end, which passes through and is splined in a boss g' on the lower side of the turret-arm e . The upper end of the screw g is screwed into the bushing g^2 , which is internally threaded and is provided with a flange on the outside lower edge. The said flanged bushing g^2 is fitted to the interior of the lug g^3 on the inside of the cutter-carrier journal e' . Surrounding said flanged bushing g^2 inside said lug g^3 and compressed between said flange and the upper side of the lug is the spiral shoe-spring g^4 . The weight of the forward end of the machine is conveyed from the lugs g^3 on the carrier-bearing, through the spring g^4 and flange-bushing g^2 , to the supporting-screw g , which rests on the floor of the room. Passing diametrically through the upper end of the flanged bushing g^2 is the pin g^5 , which fits into a slot g^7 in the adjusting-wrench g^6 and holds it from slipping when being turned by said wrench.

When the cutter-carrier rests on a solid support, any slight rise in the floor or foreign matter under the said supporting-foot raises the cutter-wheel proportionally, and this raising of the cutter-wheel makes a still greater rise in the floor, being formed by the cutter-wheel, and this is again repeated and enlarged in the succeeding cut. A depression in the floor under a solid supporting-foot likewise lowers the cutter-wheel correspondingly and to a greater extent, and the depression so made in the floor is likewise repeated and enlarged in the succeeding cut. When the cutter has raised an amount equal to the clearance allowed on the upper side between the cutter-wheel and the top of the kerf, then the wheel and possibly its carrier come in

contact with the top of the kerf and any further rising of the cutter-wheel is liable to stall the machine or break it. When the machine rests on an elastic support, however, the support itself yields to the slight elevation under it and allows the machine to pass over the obstruction without injury to itself, and where the elevation is not too great it may pass under without raising the cutter-wheel and so 5 perpetuating the elevation. In the same way should a depression in the floor occur the flexible support is forced downward to the bottom of the depression without lowering perceptibly the cutter-wheel and thereby perpetuating the depression in the cut being made. The floor thereby becomes smoother with each succeeding cut.

For raising the height of the cutter-wheel the flanged bushing g^2 is turned by the adjusting-wrench g^6 , which, by unscrewing the screw g from its bushing g^2 , raises the turret end of the machine and so the cutter-wheel e^4 , and the mine-floor slightly inclines upward as the work progresses. Of course turning 20 the bushing g^2 in the opposite direction lowers the cutter-wheel and the floor slopes downward as the work progresses.

Running longitudinally through the center of the machine-frame is the router-shaft h , 30 which is journaled at its forward end in the bushing h' , that is fastened in the middle brace c^7 by the set-screw h^2 , as shown in Fig. 4, and its rear end is journaled in bearing h^3 , that is bolted to the cross-brace c' . On the forward 35 end of said router-shaft is fastened (with a set-screw or otherwise) the beveled gear h^4 , which engages with the beveled gear d^4 , journaled on the center stud c^9 . On the rear end of the router-shaft is formed the worm h^5 , that 40 engages with the friction worm-wheel k' on the cross-feed shaft k . The said worm-wheel k' turns loosely on its shaft k between flanges k^2 k^6 , which are splined to the cross-feed shaft k , and between the friction-wheel k' and 45 flanges k^2 and k^6 are leather friction-disks k^3 . The amount of friction, and therefore the force transmitted from the worm-wheel k^2 to the shaft k , is regulated by the amount of pressure 50 on the friction-disks k^3 , which is governed by the compression of the spring k^4 , which in turn is regulated by the position of the collar k^5 , that is fastened to the shaft k by a set-screw or by other well-known means.

Running longitudinally through the turret-worm e^3 is the rotary-feed shaft q , that is journaled in the turret-bearing c^5 at its forward end and at its rear end in the right brace-bracket q' , that is bolted to the cross-brace c' and prevented from endwise motion by the 60 collar q^7 , that is held in position by screw q^8 . On the turret end of said shaft is splined the turret-worm e^3 , and on the track end is journaled the rotary-feed worm-wheel q^2 , having teeth of clutch q^3 on the side thereof.

65 Splined to and sliding longitudinally on the rear end of the rotary-feed shaft q is the clutch-sleeve q^4 , having in its end half of the

teeth of clutch q^3 that engage with the corresponding teeth in the worm-wheel q^2 . Worm-wheel q^2 is prevented from sliding into engagement with clutch-sleeve q^4 by the shoulder on shaft q . The clutch-sleeve q^4 is prevented by the collar from slipping off the end of the shaft q and the end of shaft q is squared to fit the crank-handle g^8 .

70 On the left side of the machine-frame and running longitudinally therewith is the feed-drum t , which is fastened by screw z^5 to feed-drum shaft t' , whose forward end has a bearing in the middle brace c^7 and whose rear end 80 is journaled in the left brace-bracket t^2 , that is bolted to the cross-brace c' , as shown in Figs. 1 and 6. Journaled on said drum-shaft t' is the worm-wheel t^3 , having teeth of clutch t^4 on the side thereof. Splined to and sliding 85 longitudinally on the outer end of the drum-shaft t' is the clutch-sleeve t^5 , having on its end teeth that engage with corresponding teeth on the worm-wheel t^3 , forming clutch t^6 . Worm-wheel t^3 is prevented from sliding 90 into engagement with sleeve t^5 by the shoulder on shaft t' . Sleeve t^5 is kept on the end of the shaft t' by the adjoining collar, and the end of the shaft is squared to fit the crank-handle g^8 . The details of drum-clutch t^4 are 95 similar to those of clutch q^3 , which is shown in Fig. 8.

Cross-feed shaft k , before referred to, is journaled in two bearings, the journal q^5 on its right end in the upper side of the rotary-feed bracket q' and the left end in bearing c^4 at the top of the left shoe c^3 . Keyed on the right end of cross-feed shaft k outside the bearing q^5 is the cross-feed worm q^6 , that engages with the worm-wheel q^2 . The worm q^6 105 is kept in place by the hexagonal head on the end of shaft k . Cross-feed shaft k is prevented from longitudinal motion to the right by the collar q^7 , which abuts against said bearing and is held in place by a screw in 110 the side thereof. The thrust of the spring k^4 against the friction-flange k^2 , as before referred to, is transmitted from the flange k^6 to the sleeve k^7 and to the collar q^7 . Keyed on the cross-feed shaft k and adjoining the 115 bearing c^4 is the drum-worm t^6 , that engages with drum-worm wheel t^3 , and formed on the end of worm t^6 is the ratchet-wheel t^7 , with which engages the pawl t^8 , that turns on the stud t^9 . The pawl t^8 is drawn in solid lines 120 in engagement with the ratchet-wheel t^7 and in dotted lines as out of engagement.

To withstand the powerful thrust of the cutter, which sometimes moves the ordinary tracks on the mine-floor in spite of the pressure of the jacks, my machine is provided 125 with means for grooving the mine-floor. The track is also provided with a downwardly-projecting flange y^3 , that sets in said groove and receives the said thrust. As the distance 130 from the track to the groove cutter or router is constant, each succeeding position of the track is made parallel to its previous one, so that as the work progresses the room is worked

out in a straight line at right angles with the track, so that when the track is once correctly set the pillar of coal with straight sides and uniform thickness is maintained between the rooms.

5 Journalized to swing on the bushing h' on one side and on the longitudinal feed-shaft h on the other is the router-yoke w^8 , in the center of which is journaled the shank of router-gear w' and through whose hollow center passes the router w . Fastened to the end of the shank of router-gear w' by the set-screw w^5 is the collar w^4 , as shown in section in Fig. 6. The router w is here shown as a twist-drill well backed off on the sides, so that it is adapted to cut on the side instead of the end, as ordinarily used. A reamer or any other similar tool adapted to side cutting may be used for the purpose. The router w is held 20 in place by the set-screw w^2 , which is screwed through both the collar w^4 and the shank of router-gear w' .

A rotary motion is communicated to the router by the beveled gear w^6 , which is keyed 25 on the router-shaft h and engages with the router-gear w' . To the side of the middle brace c' is bolted the router-screw bracket x' , through whose top passes the router-screw x , having the nut x^2 screwed on its end and held 30 between two projecting lugs on said bracket x' . On the opposite end of the router-screw x is an eye through which passes the bolt w^7 , on which it turns loosely and which fastens it to the router-yoke arm w^8 . To prevent injury to the router when not in use, it is swung 35 to the horizontal or nearly horizontal position shown in Fig. 6 and by the dotted lines in Fig. 7. When, however, the machine is making the straight cut and the cutter-carrier e projects out from the machine, as shown in Fig. 9, then the router is brought to the perpendicular position shown in Fig. 7 by turning the nut x^2 on the router-screw x , and when so turned the router cuts a groove y^5 in 40 the floor of the room, into which sets the downward-projecting track-flange y^8 when set for the succeeding cut. Upon the track-rails, which are designated in a general way by y , rests the rear end of the mining-machine, the 45 said rail y being made of a Z-shaped bar y' , to one flange of which is riveted the angle-iron y^2 .

On the end of one of the rails y is riveted the plate y^4 , having a jack-hole y^7 in its end. 50 The end of the abutting rail also has a jack-hole y^7 , which registers with said hole y^7 in said track-plate and when in position forms one continuous hole for the lower end of the jack y^6 when the ends of the rails y are abutting. As the track-groove y^5 is only cut from 55 the central position of the machine on the left side of the room to the central position on the right side, as shown in Fig. 11, so the flange y^8 , which sets into the groove, does not extend the full length of the track, but ends at the same point y^8 , as indicated in Fig. 11. The lower end of the track-jack y^6 is turned

cylindrical and fits into these holes y^7 , and thus holds the rails in their proper relative position, while the shoulder on jack y^6 rests 70 on top of the rails and holds them firmly to the floor. The outer ends of the rails y are also held in position by jacks in a similar manner, while the lower track-flange y^8 sets in the floor-groove y^5 , made by the router 75 during the previous undercutting.

For the purpose of guiding the machine on the track the shoes $c^2 c^3$ are furnished with downward-projecting flanges x^7 and x^8 , which engage the top of the rail on either side. For 80 preventing the machine-frame being raised from the track each shoe has a clip x^5 , sliding in a groove in the top thereof. Each clip x^5 has a hook-shaped end that engages under the top flange of the rail, as shown in Fig. 3, 85 and is held in place by the screw x^6 , which passes through a slotted hole in the clip and is screwed into a tapped hole in the shoe. When it is wanted to lift the machine from the track, the screw x^6 is unscrewed and the 90 clip is slid forward sufficient to disengage the clip from the flange of the track.

The power for operating the mining-machine is communicated to it from a motor by the driving-rope r' , which runs in the groove 95 of the driving-pulley d^6 , as shown in Fig. 9.

As before stated, Fig. 9 illustrates the machine when making the straight cut, the direction of rotation of the cutting-wheel being indicated by the arrow on its right. At the 100 right-hand end of the track is the track-bracket z , having the bracket-pulley z' attached thereto by the yoke z^2 , the said bracket z being hooked onto the end of the track y by the hook z^3 . The hauling rope or chain 105 z^4 has one end attached to the drum t by the screw z^5 and after passing around the bracket-pulley z' is attached to the bolt z^6 in the middle brace c^7 . The hauling-rope z^4 might be hitched to the end of the track; but by putting 110 the rope around the bracket-pulley z' and fastening to the machine, as here shown and described, the line of draft is brought nearer the working breast and so more nearly to the center of resistance to the moving of the machine. This lessens the friction caused by 115 the gripping action of the shoes on the track, requiring less power for feeding and less strain on the machine.

To operate the mining-machine in a mine 120 worked by the room system, the track is placed in position with its flange y^8 in the floor-groove previously cut and held by the jacks y^6 , as shown in Figs. 4 and 11. The mining-machine is placed on the track at the 125 left side of the room next the working breast, as shown in solid lines in Fig. 11, the cutter-wheel being under the middle of the machine-frame. The machine is then secured to the track by the shoe-clip x^5 , the track-bracket 130 z hooked on the right end of the track, the hauling-rope z^4 unwound from the drum t , passed around the pulley z' and secured to the bolt z^6 on the machine.

To facilitate the winding and unwinding of the rope on the drum t , the clutch t^4 is thrown out of engagement and the drum turned by the crank-handle g^8 , which fits on the end of the drum-shaft t' . The driving-rope r' after leaving the motor-pulley passes around the idlers b^5 and b^6 and the driving-pulley d^6 on the mining-machine, as shown in Fig. 9. The clutch q^3 is then engaged, and clutch t^4 and pawl t^8 are disengaged.

The power which is conveyed by the driving-rope r' to the driving-pulley d^6 is transmitted by gears d^5 , e^2 , and e^6 to the cutter-wheel e^6 , giving it a rotary motion (in the direction shown by the arrow in Fig. 1) for cutting away the coal. The power from driving-pulley d^6 is also conveyed by gears d^4 and h^4 to the router-shaft h , that carries worm h^5 , which engages worm-wheel k' on shaft k .

On the cross-feed shaft k are keyed worm t^6 , that engages worm-wheel t^3 on the drum-shaft t' , and worm q^6 , that engages worm-wheel q^2 on rotary shaft q . By engaging clutch q^3 the rotary motion of worm-wheel q^2 is transmitted to shaft q and to turret-worm e^3 , that engages the turret-worm wheel e' , and the cutter-carrier e , being bolted thereto, is given the slow rotary motion required to feed the cutter to its work. When the cutter-carrier has progressed to the outward position, (shown in Fig. 9,) the cutting feed is stopped by throwing the pawl t^8 into engagement, thus keeping the cross-feed shaft k from turning and compelling the friction-wheel k' to slide on the friction-disks k^3 on either side thereof. The clutch q^3 is now thrown out of engagement, the router gradually swung to its vertical or working position, the clutch t^4 thrown into engagement, and the pawl t^8 released. Then the straight cut across the room commences and continues to the dotted position shown on the right of Fig. 11. Again the pawl t^8 is thrown into engagement, the router swung to the horizontal position, clutch t^4 disengaged, the track-bracket z removed, the hauling-rope z^4 wound on the drum t , the clutch q^3 engaged, and when pawl t^8 is disengaged the rotary feed is again resumed. After cutting the upper right-hand corner of the room the feed is again stopped with the cutter-wheel under the middle of the machine, as shown in dotted lines on the right in Fig. 11. The driving-rope r' is now removed from the machine, the jacks taken down, the mining-machine loaded on its truck, and the track removed to one side. The coal is then brought down in the usual manner.

Sulfur balls and other obstructions are sometimes encountered in the coal, which require additional power to feed the machine and also to drive the cutter-wheel. The power employed in feeding is limited by the friction on the sides of friction-wheel k' , which is constant. Therefore when the demand for feed-power exceeds this limit the rate of progress is reduced or may be stopped entirely, thus preventing injury to the cutter-chisels

or possibly other parts of the machine. When the operator judges by the laboring of the machine that an obstruction is reached, it is preferable to stop the feed by throwing the pawl t^8 into engagement and operate the feed by hand by means of the crank-handle g^8 , which fits on the end of the cross-feed shaft k . Should the cutter be unable to cut through the obstruction, it is withdrawn from the kerf by being swung to the left, half around. The obstruction is then removed by hand and the cutting resumed as before. When the cutter e^6 is not operating on the coal, the cutter-carrier e may be more rapidly rotated by disengaging clutch q^3 and turning shaft q by means of the crank-handle g^8 , which fits on the shank on its outer end.

I have shown my mining-machine as driven by a belt or rope; but it is evident that it may be driven by means similar to those of my Patent No. 472,178 for driving mechanism, dated April 5, 1892, or my patent for a mining-machine, No. 472,177, dated April 5, 1892.

Not only is the machine adapted to be driven by a motor on a separate truck, but the motor itself may be placed on the machine-frame, a gear substituted for the pulley r^3 on the shaft h , and a pinion on the motor-shaft made to engage said gear.

Although a rope is well adapted for transmitting power to the mining-machine from a motor placed on a separate truck, yet a very compact arrangement may also be made by driving it by a belt on the dotted pulley r^3 on shaft h .

When it is desired to remove the cutters for sharpening, a hook or rope is passed through the center stud-eye d^7 and the machine is raised until the cutter-wheel clears the floor several inches. The cutter-wheel is then revolved, (either by the driving-pulley d^6 , the intermediate gear e^2 , or the cutter-wheel e^6 ,) thus bringing the cutter-chisels on its periphery successively into the position for inspection or removal for sharpening.

The pawl t^8 and ratchet t^7 might be dispensed with and the drum feed controlled by throwing the clutch t^4 in and out of gear and the rotary feed by throwing clutch q^3 in and out of gear; but these clutches cannot be engaged instantly unless the notches happen to be opposite at the time. So, also, in disengaging them the pressure between the engaging teeth is so great as to make it possibly difficult to slide the sleeve out of engagement; but the pawl and ratchet is certain, instantaneous, and easily made.

If it is desired to move the machine on the track in the opposite direction, as is sometimes the case when an obstacle is encountered, the hauling-rope is rigged with the track-bracket hooked on the left end of the track, when the winding of the hauling-rope on the drum moves the machine on the track to the left.

Although I have here shown a rotary cutter composed of a cutter-wheel with cutter-

chisels on its periphery, which is the kind I prefer, yet this may be replaced by a horizontally-revolving cutter-chain supported on the cutter-carrier and driven by a pinion on the cutter-pinion shaft. This modification is illustrated in Fig. 28 of the drawings with sufficient clearness to render more particular description unnecessary.

In the modified form of the elastic support shown in Fig. 29 the screw g has a steep spiral thread cut in its shank, which screws into the internally-screw-threaded lug. Pressure on the lower end of screw g rotates it and winds the spring at its upper end. The tension on said spring is adjusted by turning the collar g^0 on its boss, to which it is secured by one or more set-screws, as shown.

In the modified form of the router in Figs. 30 and 31 a side-milling cutter is journaled at the extremity of an arm that swings on the shaft h and is driven by a train of gears communicating motion from the spur-wheel on said shaft to the spindle on which the cutter is fastened. After what has already been said on the subject of routers this modified form will be understood without further explanation.

I have not in this application broadly claimed the cutter-fastening herein shown and described, as it forms part of my copending application, Serial No. 593,359, filed May 27, 1896, for cutter-chain for mining-machines.

Having thus described my invention, I claim—

1. The combination in a mining-machine, of a machine-frame, a cutter-carrier projecting from the forward end thereof, a horizontally-revolving cutter supported by said carrier, one or more elastic feet supporting said carrier, a rigid track supporting the rear end of said frame, means for imparting a revolving motion to said cutter and sliding said frame on said track.

2. The combination in a mining-machine of a machine-frame having track-shoes on the two rear corners thereof, a cutter-carrier journaled on the forward end thereof, a horizontally-revolving cutter journaled on said carrier, an elastic foot under said cutter-carrier, a track under said track-shoes, and means for revolving said cutter and sliding the machine on said track substantially as set forth.

3. The combination in a mining-machine of the undercutting type, of a machine-frame, a cutter-arm supported by said frame and carrying a horizontally-revolving cutter, a track-rail supporting the rear end of said frame, a hole in the forward end of the machine, a vertically-sliding plunger passing downward through said hole to the floor of the mine, a spring-cushion interposed between the machine-frame and plunger upon which is supported its forward end, together with mechanism for driving and feeding said cutter to its work.

4. The combination in a mining-machine of a machine-frame having track-shoes on its rear end, a cutter-carrier journaled in its forward end, a horizontally-revolving cutter journaled at the extremity of said cutter-carrier, a cutter-wheel pinion journaled centrally of said cutter-arm journal, and engaging said cutter, turret-screw g , on the under side of 75 said cutter-carrier, bushing g^2 , on the upper end of screw g , spring g^4 , compressed between said bushing g^2 and the cutter-arm journal, a track under said track-shoes and means for revolving said cutter-wheel pinion and moving the mining-machine on said track.

5. A mining-machine track-rail having an aperture in the end thereof, an abutting rail formed with a hole therein registering with the said aperture, in combination with a track-jack having its lower end fitting said registered holes for securing said rails together and to the floor.

6. A mining-machine track consisting of a flanged beam, an angle-bar having one limb 90 attached to the vertical flange of said flanged beam, and the other limb projecting horizontally from said flange, a flange on said track projecting below the floor-surface and engaging with a floor-groove, substantially as and 95 for the purpose set forth.

7. A mining-machine track y , having an apertured plate y^4 attached thereto, an abutting rail formed with a hole therein registering with the hole in the plate y^4 in combination with a jack y^6 having its lower end fitting said registered holes substantially as and for the purpose set forth.

8. A mining-machine track consisting of two or more abutting rails, registering holes 105 in the ends of said rails, a track-jack engaging said registering holes, a downwardly-projecting flange on said track engaging with a track-groove in the floor, an L-shaped flange projecting upward from said track, a track-shoe clip engaging said upper flange, substantially as and for the purpose set forth.

9. The combination with a mining-machine adapted to the undercutting of coal, of a track supporting the rear part thereof, said track 115 formed with a downwardly-depending edge adapted to enter and be held in a groove in the floor, and a router operatively connected with the driving mechanism of the machine and arranged to cut a groove in the floor of 120 the mine parallel with the track and in advance thereof.

10. The combination in a mining-machine of a rotating cutter journaled on a carrying-arm, a router journaled in a swinging holder 125 and adapted during its movement across the room to cut a groove therein but which may be swung above the floor to clear the said rotating cutter and carrying-arm when in their inner position, substantially as described.

11. The combination in a mining-machine of a rotating cutter journaled on a carrying-arm, of a router-shaft, a router-yoke hinged concentrically of said shaft, a horizontally-

- revolving router journaled in said yoke in operative connection with a gear on the router-shaft and adapted to cut a transverse groove in the floor of the mine when the said arm is 5 in its downward position and to swing upwardly to clear the said rotating cutter and carrying-arm when in their inner position, substantially as described.
12. In combination in a mining-machine a horizontal router-shaft and means for driving the same, a router-yoke journaled concentrically with said shaft, an arm on said router-yoke, a router-screw attached to said arm, an adjusting-nut on said router-screw 10 and lying between lugs on the router-screw bracket, together with a router journaled in said router-yoke and driven from said router-shaft, substantially as and for the purpose set forth.
13. In a mining-machine the combination with a continuously-rotating cutter-wheel, of a feed-drum shaft, a feed-drum fixed on said shaft, a worm-wheel on said drum-shaft, a cross-feed shaft journaled on the machine-frame, a friction-gear journaled on said cross-feed shaft and normally coupling the feeding-train, a worm secured to said cross-feed shaft and engaging the drum worm-wheel, a ratchet fixed on said cross-feed shaft, a pawl 15 engaging and disengaging said ratchet whereby when the pawl is in engagement with the ratchet the feed is arrested, and conversely.
14. A mining-machine frame, a cutter-carrier e projecting from the forward end thereof and carrying a horizontally-revolving cutter thereon, pinion e^9 engaging said cutter, together with gear e^2 on shaft d^2 , pinion d^3 , gear d^4 and pulley d^6 journaled on stud c^9 , gear h^4 and worm h^5 on shaft h , gear k' and worm t^6 on shaft k , worm-wheel t^8 and drum t on shaft t' , track-shoes c^2 and c^3 attached to the machine-frame and engaging track y , all combined and operated substantially as set forth.
15. The combination in a mining-machine of the machine-frame having a turret-ring on the forward end, an opening through the web of said turret-ring, flanges formed on the outside of said ring on the top and bottom sides 45 of said opening, vertical ribs at the ends of said opening connecting said flanges, a cutter-carrier having cogs on its periphery journaled in said turret-ring and carrying a horizontally-revolving cutter, a worm situated in the said opening and engaging said cogs, a shaft splined in said worm and having at its outer end means for attaching a crank-handle for operating the same substantially as set forth.
16. In a mining-machine, the machine-frame having a turret-bearing at the forward end thereof, a cutter-carrier journaled in said bearing, shaft d^2 journaled in said cutter-carrier journal, combined with gear e^2 , pinion d^5 , pulley d^6 , pinion e^9 , cutter-wheel e^6 , also gears d^4 and h^4 , shaft h , worm h^5 , worm-wheel k' , shaft k , worm q^6 , worm-wheel q^2 , shaft q , worm 60 e^3 and worm-wheel e^4 , substantially as and for the purpose set forth.
17. A spur-cog cutter-wheel, the teeth of which have radially-disposed inwardly-tapering mortises therethrough, cutter-chisels seated in said mortises, inwardly-tapering and radially-tapped dovetailed cutter-wedges fitting inwardly from the peripheral openings 75 of said mortises and adapted to be tightened in their seats by the inward pressure upon the cutter-chisels in cutting, radial wedge-screws operated from the inside of the rim engaging said wedges and drawing the same radially inward to retain the wedges in close engagement with the cutter-chisels, substantially as described.
18. In a mining-machine, a horizontally-revolving cutter-wheel consisting of a hub, a rim, and receding spokes connecting said hub and rim, of grooves on the under side of said rim in line with the front of said spokes, and cutters projecting from the rim of said wheel all combined and operating substantially as 80 and for the purpose set forth.
19. In a mining-machine in combination, a horizontally-revolving cutter-wheel consisting of a hub, a rim, and receding spokes connecting said hub and rim, and grooves on the 85 under side of said rim in line with the front of said spokes; cutting-chisels passing radially through the gear-teeth of the cutter-wheel and secured therein, wedge-screws passing through said rim and serving to secure said 90 chisels substantially as and for the purpose set forth.
20. In a mining-machine, a revolving turret on the forward end thereof, a gear-wheel journaled in said turret, a cutter-carrier on the 105 under side of said gear-wheel carrying on its outer end a horizontally-revolving cutter consisting of a cutter-wheel having receding spokes and grooves on the under side of said rim in line with the front of said spokes, cutting-chisels on the periphery passing radially through the gear-teeth of the cutter-wheel and held in place by radially-tapped cutter-wedges, wedge-screws passing radially through said rim and engaging said wedges, 110 substantially as and for the purpose specified.
21. In a mining-machine, a cross-feed shaft k , carrying worm q^6 on said shaft, worm-wheel q^2 , shaft q , worm e^3 , worm-wheel d^4 attached to the rotating arm e for operating the rotary-feed motion of the mining-machine, and worm t^6 , worm-wheel t^8 , shaft t' carrying the drum t , for operating the straight feed and friction gear-wheel k' , substantially as set forth.
22. In a mining-machine a cross-feed shaft 125 k , worm t^6 thereon engaging the drum worm-wheel t^8 , and shaft t' carrying drum t and worm q^6 engaging the rotary-feed worm-wheel q^2 , shaft q , worm e^3 , worm-wheel d^4 attached to the rotating arm e , friction-gear k' on said 130 shaft, ratchet-wheel t^8 fixed on said shaft, pawl t^8 engaging said ratchet, substantially as and for the purpose set forth.
23. In a mining-machine the combination

of the machine-frame having a turret-ring on its forward end, a cutter-carrier journaled within said turret-ring and having cogs on the periphery of said journal within said ring, 5 and a worm engaging said cogs, substantially as described.

24. The combination in a mining-machine of the machine-frame having a turret-ring on the forward end, an opening through the web 10 of said turret-ring, flanges formed on the outside of said ring on the top and bottom sides of said opening, vertical ribs at the ends of said opening connecting said flanges, a cutter-carrier journaled within said turret-ring 15 and having cogs on the periphery of said journal within said ring, and a worm journaled in the said opening and engaging said cogs, substantially as described.

25. In a mining-machine, the combination with the machine-frame of a turret-ring 20 thereon having a worm-housing substantially as described, formed on the side thereof, a cutter-carrier arm having a journal fitting the interior of said turret, said journal having a worm-gear cut into its periphery at its middle part and having a bearing on the interior of said turret each side of said gear, and a worm situated in said housing and engaging the gear on said journal, substantially as described. 25
